CLAIM

The ornamental design for handle, as shown and described.

DESCRIPTION

FIG. 1 is a perspective view of handle showing an embodiment of my new design;

FIG. 2 is a left side elevation view thereof, the right side elevation view thereof being a mirror image;

FIG. 3 is a top plan thereof, the bottom plan view thereof being a mirror image;

FIG. 4 is a front elevation view thereof;

FIG. 5 is a rear elevation view thereof;

FIG. 6 is a perspective view of handle showing another embodiment of my new design;

FIG. 7 is a left side elevation view thereof, the right side elevation view thereof being a mirror image;

FIG. 8 is a top plan thereof, the bottom plan view thereof being a mirror image;

FIG. 9 is a front elevation view thereof;

FIG. 10 is a rear elevation view thereof;

FIG. 11 is a perspective view of handle showing yet another embodiment of my new design;

FIG. 12 is a left side elevation view thereof, the right side elevation view thereof being a mirror image;

FIG. 13 is a top plan thereof, the bottom plan view thereof being a mirror image;

FIG. 14 is a front elevation view thereof; and,

FIG. 15 is a rear elevation view thereof.

The broken lines shown herein are for illustrative purposes only and form no part of the claimed design.
